J. P. N. WOOD

FIRE POT MOLD

Filed May 21, 1927

Patented Apr. 10, 1928.

1,665,650

UNITED STATES PATENT OFFICE.

JOHN PAUL NICHOLAS WOOD, OF EAST WINTERHAVEN, FLORIDA.

FIRE-POT MOLD.

Application filed May 21, 1927. Serial No. 193,143.

The object of the invention is to provide a simple and efficient device by means of which a fire-pot, such as is adapted for the burning of fuel in orchards and the like to protect vegetation from frost, may be readily molded; and to provide a device of this character in which the several elements may be readily assembled in their proper relation without the necessity for the exercise 10 of particular care in securing their proper relation.

With this object in view, the invention consists in a construction and combination of parts of which a preferred embodiment is 15 illustrated in the accompanying drawings, wherein:

Figure 1 is a side elevational view of the invention.

Figure 2 is a vertical sectional view on the 20 plane indicated by the line 2—2 of Figure 1.

Figure 3 is a horizontal sectional view on the plane indicated by the line 3—3 of Figure 1.

Figure 4 is a central vertical sectional 25 view of the molded product.

Figure 5 is a perspective view illustrating the carrying tongues for the molded fire-pot.

The device comprises the hollow core 10 and the shell 11, both being of inverted 30 frusto-conical shape, since it is essential that the molded fire-pot be of such shape. The shell comprises the sections 11^a and 11^b, each transversely semicircular in form and each on its opposite edges being formed 35 with a series of spaced tongues rolled to provide sleeves 12 which, when the two sections are disposed together, are in intercurrent relation and receive the locking rods 13, the latter at their upper ends being provided 40 with handles 14 by which the rods may be withdrawn and inserted in the assembling and disassembling of the shell. The two sections of the shell are provided each with a radially extending foot 15 formed 45 with perforations for the reception of nails or fasteners 16 by means of which the shell may be secured in position on the supporting surface.

The molded product 17, indicated in section in Figure 4, is open at its lower end as well as at the upper end, being designed 50 to seat upon the ground. The draft openings 18, which are formed at the lower edge of the fire-pot 17, result from the placement 55 of the arch plates 19 at the lower edge of the shell 11. There may be as many of these

arch plates as desired but it is thought that three will be sufficient, since three openings will readily provide the necessary draft for the fire-pot. The width of the arch 60 plates 19 is half the distance between the interior diameter of the shell at the lower end and the outer diameter of the core 10. The arch plates are secured to the shell in any appropriate manner, the core engaging edges being formed to a shorter radius than the shell engaging edges. This construction provides a tapering shape 65 transversely for the arch plates, so that the sections of the shell may be readily removed 70 from the molded product after casting the latter.

The core 10 is retained in its position within the shell, so that it may not rise from the latter during the operation of casting the 75 fire-pot, the means for retaining it consisting of a plurality of anchoring hooks 20 engaged with ears 21 secured on the inner surface of the core and anchored to the supporting surface in any acceptable manner, as by nails 80 or, as shown, by staples 22 with which the extremities of the anchoring hooks 20 engage. In the molding operation the core is first placed and the anchoring hooks 20 secured, after which the shell is disposed in 85 surrounding relation to the core, the arch plates 19 serving as separators representing the thickness of the wall of the cast firepot.

The feet 15, of course, serve to hold the 90 shell in position but as a further assurance against it moving at its upper end when the loose material is being poured in, brace rods 24 are provided, having hooked terminals engaged with ears 23 disposed on the outer 95 surface of the two sections of the shell adjacent the upper ends of the latter, the remote ends of the brace rods being secured to the supporting surface by appropriate fasteners such as nails, or, as shown, by 100 staples 25 with which the extremities of the rods are engaged.

In the molded fire-pot a grate is used consisting of a piece of wire netting 26 cut to circular form and of sufficient diameter 105 to engage the wall of the pot above the openings 18.

The carrying tongues illustrated in Figure 5 consist of complementary elements 27 formed with intermediate semicircular oppositely disposed arch portions 27^a from which emanate at opposite ends the radial portions of 110

which the portions 27^b are hingedly connected as indicated at 28, the straight or radial portions 27^c being unconnected. The tongues constitute a carrying means for the 5 cast fire-pot, the two elements being swung apart to dispose the arch portions 27^a in surrounding relation to the pot when the straight portions 27^b and 27^c constitute handles by means of which the pot may be 10 carried.

The invention having been described, what is claimed as new and useful is:

1. A mold for the purpose indicated comprising a core provided with anchoring hooks 15 for securement to a flat surface, and a shell disposed in surrounding relation to the core and comprising separable sections, the shell at its lower end being provided with arch plates serving as spacers between the core 20 and the shell and defining bottom openings in the molded product, the arch plates being of transversely tapering form.

2. A mold for the purpose indicated comprising a core provided with anchoring 25 means, a shell consisting of complemental

sections provided with intercurrent sleeves, rods having handles formed at their upper ends and engageable in said sleeves, and arch plates secured to the shell at the lower edge and serving as spacers between it and the core, the latter being hollow with the anchoring means disposed within it. 30

3. A mold for the purpose indicated comprising a core provided with anchoring means, a shell consisting of complemental 35 sections provided with intercurrent sleeves, rods having handles formed at their upper ends and engageable in said sleeves and projecting beyond the lower edge of the shell to provide anchoring points, arch plates secured to the shell at the lower edge and serving as spacers between it and the core, and brace rods detachably connected with the shell at the upper edge and provided with means for anchoring them in the plane of 40 the bottom edges of the core and shell. 45

In testimony whereof he affixes his signature.

JOHN PAUL NICHOLAS WOOD.
